NUMERICAL CONTROL SYSTEM CABINET

Allen R. Perrins, Cheshire, and Paul D. Henderson, Avon,
Conn., assignors to The Superior Electric Company,
Bristol, Conn.

Filed Nov. 14, 1972, Ser. No. 306,396

Term of patent 14 years

Int. Cl. D14—01, 02
U.S. Cl. D26—5 C

Fig. 1

Fig. 2

Fig. 3

FIG. 1 is a front perspective view of a numerical control system cabinet showing our new design;

FIG. 2 is a front view thereof; and

FIG. 3 is a side view thereof.

The tape reels shown in FIG. 2 are shown in broken lines for illustrative purposes only and form no part of the claimed design invention. The side of the article, not shown, and the rear, are unornamented.

We claim:

The ornamental design for a numerical control system cabinet, as shown and described.
